UNITED STATES PATENT OFFICE

2,152,911

CAFTON

Paul A. Nemoede, Louisville, Ky., assignor to Container Corporation of America, Chicago, Ill., a corporation of Delaware

Application February 14, 1938, Serial No. 190,475

7 Claims. (Cl. 229—16)

This invention relates to folding boxes which may be manufactured from a single sheet of paper, paper-board, fiber-board etc., and, more particularly to a box or container peculiarly adapted for the packaging, shipment, display and retail as well as wholesale dispensation of commodities such as mushrooms.

One of the primary objects of the invention is to provide a relatively simple and inexpensive type of box or container which, having provision for deflection or expansion, may be utilized for the packaging of a commodity such as mushrooms which, after being picked increase in size or assume a different shape thereby occupying or demanding an increased space over that originally required. It is estimated that normal growth or expansion of mushrooms after being picked and packed may necessitate the provision of as much as ten per centum (10%) of expansion space.

Another important object is to provide a box or container of such construction that it may not only be quickly and readily formed or folded from pre-cut and scored blanks, in which form it is most easily and economically shipped, but so constructed that it may be easily and conveniently filled or packed and thereafter closed.

Still another major object is to provide a box of such character that it may be filled completely even though the commodity may later expand or swell, the construction being so arranged that the walls of the box and one wall in particular may deflect or bulge to accommodate the expanded or enlarged volume of the commodity packaged within the box.

A further object is to provide a novel closure locking and releasing means whereby the box may be quickly and easily closed and secured in closed condition after being filled and of such nature that the ultimate consumer or anyone else may as readily and quickly open the box for removal or inspection of the contents. Furthermore, the closure construction is such that the normal position of the box on its bottom may assist in maintaining the closure in closed or secured position and also against spilling or loss of the box contents should the closure fastening or locking means become released.

Many other objects as well as the advantages and uses of the invention will be appreciated and understood after reading the following description of a preferred embodiment, after reading the claims and after viewing the drawing in which:

Fig. 1 is a perspective view of a box constructed in accordance with one preferred embodiment of the invention.

Fig. 2 is a vertical section taken substantially along the line 2—2 of Fig. 1, and

Fig. 3 is a development or plan view of the sheet of paper board or other material as cut and scored ready for formation or folding into the box of Figs. 1 and 2.

The box chosen for illustration of the invention is one which may be utilized for the display packaging of mushrooms and is of generally cubical shape having four (4) side walls, a top wall and a bottom wall, all integral with one another, that is, all formed from a single sheet and connected with one another in that sheet. Fig. 3 illustrates the character of the blank as it appears after being cut out in the desired shape and scored for the necessary folding.

The blank is cut and scored to provide a top panel or section 4 in which a window opening 5 may be provided, a pair of side wall forming panels or sections 6 each of which carries a pair of side wall locking wings or flaps 7 and 8, a pair of side wall panels or sections 9 and 11, a bottom wall forming panel or section 12, a locking tab 13 on the side wall panel 9, a flange or flap 14 on the panel 12, a slit 15 through panel 12 adjacent to flange 14, and a locking tongue 16 on each of the wings or flaps 7 and 8. Since the box is to be used for mushrooms, it is also provided with a suitable number and arrangement of apertures 17 and 18 whereby satisfactory ventilation may be assured. The window opening 5 may be covered with "glassine" or "cellophane" 19 or may be left open if its size and the relative size of the packaged commodity permit, or may be omitted altogether. Score lines 21 segregate the top wall panel section 4 from the side wall panels 6, 9 and 11, score lines 22 segregate the side wall locking flaps 7 and 8 from side wall panels 6, and score lines 23 and 24, respectively segregate the bottom wall panel 12 from side wall panel 11 and flange or flap 14 from panel 12.

It will be noted that the box bottom wall is inset or raised above the bottom edges of the box side walls and to this end the side wall panels 9 and 11 are made shorter (in distances measured perpendicular to score lines 21) than the side wall panels 6. And, to the same end, the bottom edges of the side wall locking flaps 7 and 8 are coextensive (in effect) with the bottom edges of side wall panels 6; also, the width of flange or flap 14 (measured perpendicular to score line

24) is equal or substantially equal to the distance to which the bottom wall 12 is inset from or raised above the bottom edges of the side walls 6 and flaps 7 and 8. The box illustrated has a top 5 of greater dimensions than its bottom and the cutting and scoring pattern is in accord therewith.

The formation of the box from the blank of Fig. 3 is a simple and easy matter. Preferably 10 placing the blank flat with the side to which the window material has been applied uppermost, the side wall panels 6, 9 and 11 are folded upwardly on score lines 21 until their side edges come together whereupon the locking flaps 7 are folded 15 toward one another over side panel 9 and the tongues 16 are interlocked, one behind the other. The locking tab 13 will then project upwardly alongside of the inside of the inside surfaces of flaps 7. In like manner the locking flaps 8 are 20 interlocked with one another outside of panel 11 through their tongues 16 and the bottom panel 12 and flange 14 may be permitted to project upwardly until the mushrooms or other commodities 25 have been packed within the box from the bottom thereof.

After packing, the bottom wall panel 12 is folded down about score line 23 toward its final position and flange 14 is bent upwardly (toward the observer) about score line 24. Then the tab 30 13 may be directed through the slit 15 as the flange 14 and panel 12 are moved into their final positions as illustrated in Figs. 1 and 2. In this position the flange 14 projects between the tab 13 and the interior faces of the flaps 7 and is so 35 disposed as to be readily available to be pulled out carrying the bottom panel with it. The bottom edge of the flange 14 will be approximately along and even with the bottom edges of flaps 7 so that the edge will assist in supporting the load 40 of the box contents. It is apparent that the insertion of the tab 13 into the slit 15 will not cause any substantial deflection of the tab from the plane of its attached side wall panel 9. The slit 15 being of irregular shape (substantially 45 W-shape) the friction and interlocking connection between tab 13 and the edges of the slit will afford substantial support, under normal conditions, for the load on the box bottom wall. Since the bottom wall is supported at two edges only it 50 is free to bulge or to expand with expansion of the box contents.

While the invention has been disclosed in a preferred embodiment it will be apparent that it is susceptible of other forms and various arrangements wherefore it is not intended that it shall be limited except by its spirit and the scope of the appended claims.

I claim:

1. A box of the character described comprising, 60 a single sheet of material cut, scored and folded to provide a generally cubical container having a top wall, side walls attached to said top wall, a bottom wall disposed above the bottom edges of the side walls and integrally attached along one 65 edge to one of said side walls, the opposite edge of said bottom wall having a downwardly extending flange normally disposed in proximity to a bottom edge portion of the adjacent side wall, a locking tongue on said side wall, said bottom wall having a slit of irregular form in length therethrough adjacent to said flange and arranged to releasably receive the locking tongue to interlock said side wall with the bottom wall.

2. A shipping box for mushrooms and the like comprising, a single sheet of material such as

paper board cut, scored and folded to provide a container having four side walls, a top wall and a bottom wall, said top wall being formed in rectangular shape from a central panel of the sheet and having a sight opening therethrough, each of one pair of opposite side walls being attached along its top edge to and extending downwardly from an edge of the top wall and having a laterally extending locking flap at and coextensive with each side edge, each of the other pair of side walls being attached along its top edge to and extending downwardly from an edge of the top wall and being of a lesser length, from top to bottom edges, than the first said pair of side walls, a rectangular bottom wall secured along 15 one of its edges to the bottom edge of one of said other pair of side walls, and interlocking means for securing the opposite edge of said bottom wall to the bottom edge of the other of said other pair of side walls, directly opposed locking flaps being 20 folded over the outer face of the contiguous of said other pair of side walls and interlocked with one another thereover.

3. A shipping box for mushrooms and the like comprising, a single sheet of material such as 25 paper board cut, scored and folded to provide a container having four side walls, a top wall and a bottom wall, said top wall being formed in rectangular shape from a central panel of the sheet, each of one pair of opposite side walls being attached along its top wall and having a laterally extending locking flap at each side edge, each of the locking flap bottom edges terminating substantially flush with the bottom edge of its attached side wall, each of the other pair of side 30 walls being attached along its top edge to and extending downwardly from an edge of the top wall and being of a lesser length, from top to bottom edges, than the first said pair of side walls, a rectangular bottom wall secured along one of its 35 edges to the bottom edge of one of the shorter side walls, and interlocking means for securing the opposite edge of said bottom wall to the bottom edge of the other shorter side wall, directly opposed locking flaps being folded over the outer 40 face of the contiguous of said other pair of side walls and interlocked with one another thereover.

4. A shipping box for mushrooms and the like comprising, a single sheet of material such as 45 paper-board cut, scored and folded to provide an even multiple sided central panel defining a top, a panel integral with each side of said central panel and extending downwardly therefrom to form a side wall of the box, each of alternate side panels having a locking flap integral with 50 each of the lateral edges thereof, the adjacent locking flaps of alternate side panels being arranged to overlap the intermediate side panel and to interlock with one another at the outer face of the intermediate side panel, one of the intermediate side panels terminating above the bottom edges of adjacent side panels and having a locking tab attached to the bottom edge thereof, the side panel opposite to said one intermediate panel terminating above the bottom edges of adjacent 55 side panels and having a bottom forming panel attached thereto at its bottom edge, said bottom panel having a slit for reception of said locking tab and being unconnected with all other side panels.

5. A shipping box comprising a single sheet of material such as paperboard cut, scored and folded to provide a rectangular central panel defining a top, a panel integral with each side of said central panel and extending downwardly

therefrom to form a side wall of the box, each of two alternate side panels having a locking flap integral with each of the lateral edges thereof, the adjacent locking flaps of said alternate side panels being arranged to substantially completely overlap each of the remaining alternate side panels and to interlock with one another at the outer face of each of such side panels, one of said remaining side panels having a locking tab extending from the bottom thereof, a bottom panel extending from the side panel opposite to the side panel carrying the locking tab, said bottom panel having an extension flange thereon, there being a slit formed along the meeting edges of the bottom panel and extension flange for the reception of said locking tab.

6. A shipping box comprising, a single sheet of material such as paperboard cut, scored and folded to provide a rectangular central panel defining a top, a panel integral with each side of said central panel and extending downwardly therefrom to form a side wall of the box, each of alternate side panels having a locking flap integral with each of the lateral edges thereof, the adjacent locking flaps of alternate side panels being arranged to overlap the intermediate side panel and to interlock with one another at the outer face of the intermediate side panel, one of the intermediate side panels terminating above the bottom edges of adjacent side panels and having a bottom forming panel attached thereto at its bottom edge, and means for connecting the bottom panel to the opposite side panel above the bottom edges of the adjacent side panels.

7. A shipping box comprising, a single sheet of material such as paperboard, cut, scored and folded to provide a rectangular central panel defining a top, a panel integral with each side of said central panel and extending downwardly therefrom to form a side wall of the box, each of alternate side panels having a locking flap integral with each of the lateral edges thereof, the adjacent locking flaps of alternate side panels being arranged to overlap the intermediate side panel and to interlock with one another at the outer face of the intermediate side panel, one of the intermediate side panels terminating above the bottom edges of adjacent side panels and having a bottom panel attached thereto at its lower edge, said bottom panel having an extension flange thereon, there being a slit formed along the meeting edges of the bottom panel and the extension flange for the reception of a locking tab, a downwardly projecting locking tab disposed in the lower portion of the side wall panel opposite to the one carrying the bottom panel, said locking tab having lateral extensions thereon for engagement within said slit, the engaging parts of the lateral extensions being located above the bottom edges of the adjacent side panels, and the slit being so related to the locking tab that engagement of the tab in the slit is effected without substantially deflecting the locking tab from the general plane of its attached side panel.

30
